JOSEPH M. KARL, OF ROSLYN HEIGHTS, NEW YORK, ASSIGNOR, BY DIRECT AND MESNE ASSIGNMENTS, TO ROSLYN SPECIALTY COMPANY, INC., OF ROSLYN, NEW YORK, A CORPORATION OF NEW YORK.

STOP-CATCH.

1,195,166.

Specification of Letters Patent. Patented Aug. 15, 1916.

Application filed November 9, 1915. Serial No. 60,434.

To all whom it may concern:

Be it known that I, JOSEPH M. KARL, a citizen of the United States, and a resident of Roslyn Heights, in the county of Nassau 5 and State of New York, have invented a certain new and useful Improvement in Stop-Catches, of which the following is a full, clear, and exact specification.

This invention relates to a class of devices adapted to be used in conjunction with doors and the like.

My invention has for its object primarily to provide a stop-catch designed to be employed for limiting the movement of a door, 15 or the shutter of a window and the like when swung open to suitable distances as well as for releasably retaining, the door, or shutter in open positions, the device also serving to prevent the knob of the door 20 from damaging the adjacent wall by contacting therewith, and for serving to prevent the shutter when used thereon from rattling during windy weather. This is accomplished mainly by providing a tubular 25 member having an angularly projecting arm, adapted to be fastened to a support in the path of movement of a door whereby the tubular member may be spaced a suitable distance from the support, and adapted 30 to be secured on the door is a coöperating member with two spaced extensions to freely accommodate the tubular member therebetween, the extensions having recesses in opposed relation to the open ends of the tubular member. Movable in the open ends of 35 the tubular member are two substantially spherical locking elements normally disposed partially out of the tubular member for being releasably seated in the recesses 40 of the coöperating member when the door is opened a distance whereby the door will be held against movement.

Another object of the invention is to provide in the tubular member between the 45 locking elements a spring, or resilient element serving to yieldingly force the locking elements outwardly of the open ends of the tubular element.

A further object of the invention is to 50 provide a stop catch of a simple, efficient and durable construction, and which may be made in any desired size.

A practical embodiment of the invention 55 is represented in the accompanying drawing forming a part of this specification in

which similar characters of reference indicate corresponding parts in all the views, the said invention being more fully described hereinafter, and then pointed out in the claims at the end of the description. 60

In the drawing, Figure 1 is a fragmentary detail sectional view, showing a door and its support with one form of stop-catch embodying my invention applied thereto. Fig. 2 is a side elevation of the 65 stop-catch. Fig. 3 is a section taken on the line III—III of Fig. 4. Fig. 4 is a top plan of the stop-catch, and Fig. 5 is a section taken on the line V—V of Fig. 2.

The device, or stop catch has a tubular 70 member 10 and a complementary coöperating recessed member, as 11. The tubular member 10 may be of any desired diameter and length, and projecting angularly preferably from the central part of the tubular member 75 is an arm 12 to form this member in substantially a T-shape. The arm 12 is of a length so as to space the tubular member proper a suitable distance from a support, as 13, to which a door, as 14, or the shutter 80 of a window, and the like may be hingedly swung, and the free end part of this arm, in practice, is secured to the support by any desired means, for instance by a screw, as 15, so that the tubular member will be in 85 the path of the door when swung open.

The coöperating member 11 may be approximately U-shaped to provide a transverse plate 16 from which two extensions 17 and 18 are disposed in right angular 90 directions, and these extensions are spaced from each other a distance to freely accommodate the tubular member 10 therebetween. Through the transverse plate 16 of the U-shaped member 11 may be a number of 95 holes 19 to permit the member to be fastened to the door by screws, or otherwise in a position in opposed relation to the tubular member so that the U-shaped member will straddle the tubular member on the door 100 being swung open a suitable distance, as will be hereinafter more fully described, and the parts of the extensions 17 and 18 of the U-shaped member in opposition to the open ends of the tubular member are respectively 105 recessed, at 20 and 21, for being registered with the open ends of the tubular member and for reception of locking elements 22 and 23 which are yieldingly movable in the open ends of the tubular member 10 where- 110

by the U-shaped member and the tubular member may be releasably held together.

- The locking elements 22 and 23 are preferably substantially spherical in shape. 5 These spherical locking elements are normally arranged to partially protrude from the open ends of the tubular member, and to prevent the locking elements from accidental displacement in the tubular member 10 its open ends are slightly reduced in diameter.

In order to yieldingly force the locking elements 22 and 23 outwardly of the tubular member for being seated in the recesses 20 15 and 21 of the U-shaped member, in the tubular member between the locking elements there is a resilient element, or spring, as 24. This spring is tensioned so that when the device is applied to a door and its support, 20 as above explained, and the door is swung open for the locking elements to be seated in the recesses of the U-shaped member 11, the engagement between the locking elements and the extensions 17 and 18 of the 25 U-shaped member will serve to releasably hold the door open. Moreover, by making the arm 12 of the member 10 of sufficient length, the door will be spaced from an adjacent wall to prevent it from being 30 damaged by contact of the door knob therewith, and when the device is employed in a similar manner for releasably holding a window shutter open it will also serve to prevent the shutter from rattling during 35 windy weather.

In the foregoing description, I have embodied the preferred form of my invention, but I do not wish to be understood as limiting myself thereto, as I am aware that 40 modifications may be made therein without departing from the principle, or sacrificing any of the advantages of this invention, therefore I reserve to myself the right to make such changes as fairly fall within the 45 scope thereof.

Having thus described my invention, I claim as new and desire to secure by Letters Patent:—

1. In a stop-catch of the character described, a tubular member adapted to be secured on a support to which is hinged a door or the like, a complemental member adapted to be fastened on the door, the said complemental member having two spaced recesses for registration with the open ends of the tubular member when the door is swung open, and two yieldingly movable locking elements in the tubular member, one partially protruding from each open end of the tubular member so as to be seated in the recesses of the recessed member when the recesses and the open ends of the tubular member are in register, for the purpose specified. 55
- 60 65 70 75 80 85 90 95 100 105 110 115 120 125 130

scribed, a tubular member having a projecting arm adapted to be secured on a support to which is hinged a door or the like so that the tubular member will be spaced from the support, a complemental member adapted to be fastened on the door, the said complemental member having two spaced extensions to accommodate the tubular member therebetween, and the extensions having recesses for registration with the open ends of the tubular member when the door is swung open, and two yieldingly movable locking elements in the tubular member, one partially protruding from each open end of the tubular member so as to be seated in the recesses of the recessed member when the recesses and the open ends of the tubular member are in register, for the purpose specified.

3. In a stop-catch of the character described, a tubular member adapted to be secured on a support to which is hinged a door or the like, a complemental member adapted to be fastened on the door, the said complemental member having two spaced recesses for registration with the open ends of the tubular member when the door is swung open, and two yieldingly movable substantially spherical locking elements in the tubular member, one partially protruding from each open end of the tubular member so as to be seated in the recesses of the recessed member when the recesses and the open ends of the tubular member are in register, for the purpose specified.

4. In a stop-catch of the character described, a tubular member adapted to be secured on a support to which is hinged a door, or the like, a complemental member adapted to be fastened on the door, the said complemental member having two spaced recesses for registration with the open ends of the tubular member when the door is swung open, two movable substantially spherical locking elements in the tubular member, one partially protruding from each open end of the tubular member so as to be seated in the recesses of the recessed member when the recesses and the open ends of the tubular member are in register, and a spring in the tubular member between the locking elements, serving to normally force the locking elements outwardly of the tubular member, for the purpose specified.

5. In a stop-catch of the character described, a tubular member having an angularly projecting arm with means to secure the arm on a support to which is hinged a door, or the like so that the tubular member will be spaced from the support, a complemental member adapted to be fastened on the door, the said complemental member being substantially U-shaped to provide two spaced extensions to freely accommodate the tubular member therebetween, and the two

extensions having recesses for registration with the open ends of the tubular member when the door is swung open, two movable substantially spherical locking elements in 5 the tubular member, one partially protruding from each open end of the tubular member so as to be seated in the recesses of the recessed member when the recesses and the open ends of the tubular member are in 10 register, and a spring in the tubular member

between the locking elements, serving to normally force the locking elements outwardly of the tubular member, for the purpose specified.

This specification signed and witnessed 15 this eighth day of November, A. D. 1915.
